TO LINK-BELT COMPANY, OF CHICAGO, ILLINOIS, A CORPORATION OF ILLINOIS

METHOD OF REDUCING CLEARANCE WIDTH OF CRAWLER CRANES

Application filed May 17, 1928. Serial No. 278,556.

Our invention relates to improvements in crawler cranes, shovels, etc., and has for one object to provide a new and improved means whereby the overall width of crawler machines may be reduced for shipment.

Large size crawler machines require relatively wide and heavy traveling treads which project laterally beyond the space occupied by the working platform lower framework, upper 10 rotating base and house. In order that a crawler machine may be shipped by rail, the dimensions of the various parts may be made just as big as they can be to accommodate the machinery while still falling inside 15 railroad clearance dimensions. The traveling treads themselves must of necessity for some machines project beyond the railroad clearance limits and so when the machine is to be shipped by rail, it frequently becomes 20 necessary to remove the traveling treads or otherwise dismantle the machine. In our solution of the problem we propose to place on the railroad car a track narrow enough to come within railroad clearance limits upon 25 which the supporting roller or sprockets which ordinarily ride upon the traveling treads may travel and be supported. This track may take the form of a rigid straight section just long enough to support the rollers and sprockets or may take the form of 30 articulated sections of necessary length laid on the car. In either case such section may terminate in railroad stop members so that when the machine is run onto the car and 35 onto the auxiliary portable track sections, it engages the forward stops at the end of the track sections which preferably forms a part of or is attached thereto and thereby longitudinal movement of the crawler crane is 40 prevented. After the crane has been moved onto the tracks and has engaged the stop at the front end a second stop will be positioned at the rear end of the tracks to hold the machine against forward and backward movement and the tracks themselves will prevent side movement as they are confined between 45 the rollers and sprockets.

If the machine is of the type where the driving sprockets are also supporting rollers or of the type where the driving and take up 50

sprockets are on the same horizontal plane as the supporting rollers, then by using a type of track with teeth or lugs to engage the sprockets the machine can move itself up into place on the tracks by use of its own 55 driving mechanism. If, however, the machine is of the common type where the driving and take-up sprockets are above the supporting rollers this cannot be done. In this case, it is only necessary to lead one of the 60 cables out from the machine and attach it to an anchor and the machine can then pull itself onto and along the track by its own power.

Our invention is illustrated more or less 65 diagrammatically in the accompanying drawings, wherein—

Figures 1, 2 and 3 and 4 show diagrammatic side elevation and plan view of the various operations from the time the machine 70 is moved onto the car under its own power with the traveling treads to the time when it is positioned on a railroad car for shipment with the traveling treads removed;

Figure 5 is a detail side and end view of 75 the traveling tread;

Figure 6 is a side elevation and section through the shipping treads.

Like parts are indicated by like characters 80 throughout the several figures.

A is a railroad car of the usual type. A¹ is the crawler truck having supporting rollers A², take-up sprockets A³, drive sprockets A⁴ and a closed continuous traveling tread A⁵ on each side. A⁶ is the turn table. A⁷ is the 85 machinery and operator's house containing the engine and controller mechanism for performing all the working functions of the machine.

B is a winding drum, B¹ a cable leading 90 forward from the winding drum and anchored at the forward end of the car or other fixed point whereby the machine may pull itself along the tracks by winding up the cable on the drum independent of the propelling machinery operating the drive sprockets. B² B³ are relatively narrow supporting tracks. They are articulated and so built as to engage the rollers A² and sprockets A³ A⁴ in exactly the same manner as the traveling 95 100

tread A⁵. B³ are similar tracks except that they are of one piece. It will be noted that the tracks B² which are articulated may be made up of longer links than the track A⁵, this being permissible because they are articulated merely for convenience in handling since they rest on the car floor and do not tend to encircle take-up and driving sprockets as do the traveling treads. B⁴ are stop members mounted on the tracks B² or B³ as the case may be. These stop members may be held in position with respect to these tracks in any suitable way either by being bolted to them or as shown in Figure 4 by being articulated to the end of the track. These stop members B⁴ and B⁵ engage the sprockets and limit the forward or backward movement of the machine.

The use and operation of this invention are as follows:

20 The machine is run onto a railroad car in the usual manner just as it is maneuvered in any space on any platform until it reaches the position shown in Figure 1. In the meantime the shipping tracks will have been properly 25 placed on the railroad car floor. The ordinary traveling treads will be disconnected at the joint C and connected to the end of the shipping tracks, B². The remainder of the traveling treads extending from the joint 30 C around the take-up sprockets across the supporting rollers and about the driving sprockets, will be moved backward and piled upon the car as shown at C¹. The machine will then be moved forward into the position 35 shown in Figure 3. This being done either by winding up the cable as above pointed out or by the drive sprockets. They are properly located to engage the shipping tracks. The end of the traveling treads at C² will be disconnected 40 from the shipping tracks and the traveling treads sections will be disposed as indicated at C³ or otherwise so as to distribute the weight along the car floor. The stops B⁴ if not already in place, will be put in place 45 as indicated in Figure 4 and the stops B⁵ will be put in place, the house and machine frame will be blocked or anchored in position in the usual manner on the car and the apparatus will then be ready for shipment.

50 When the destination is reached and it is desired to unload and put the machine into service, the operations are reversed. The stop B⁵ is removed, the traveling treads are connected to the shipping tracks, the machine 55 either moves itself back off the shipping tracks or is rotated through an angle of 180° and the cable anchored to the other end of the car or some other fixed point. The cable is wound up and moves the machine off the shipping tracks onto the traveling treads. The traveling treads are piled up as indicated in Figure 3, the machine is moved back to its 60 Figure 2 position, the traveling treads and shipping tracks are disconnected and the 65 traveling treads are assembled and connected

up around the sprockets and rollers as indicated in Figure 1.

In this connection, it will be noted that the traveling treads overhang the car platform as shown in Figures 1, 2 and 3. After the 70 machine has been moved off the traveling treads and they are disconnected, the treads must be moved inwardly into the position shown in Figure 4 to provide clearance.

For purposes of convenience and illustration we have discussed our application in terms of railroad clearance as under most conditions it is the protection of a device which will fall within railroad clearance. It is highly important but it must nevertheless be understood that under many conditions our invention is equally applicable to a device which may fall well inside railroad clearance or well outside railroad clearance but nevertheless falls within certain predetermined and arbitrary clearance ranges for instance in connection with tunnel work our invention is applicable or in connection with other shipment or any other conditions where it is necessary to have a device which can be 80 reduced for transportation within certain predetermined clearances to a point where its dimensions are smaller than they are in working operation.

We claim:

1. The process of preparing crawler vehicles for railroad shipment which consists in moving the vehicle under its own power into position on a railroad car, disconnecting the traveling treads or tracks adjacent one end 100 of the vehicle, moving each upper portion of the disconnected track longitudinally backward to clear the vehicle and piling such track on the car, connecting the forward ends of the traveling treads or tracks with a shipping track placed on the car, moving the vehicle 105 forwardly along the traveling treads and onto the shipping tracks, locking the vehicle in place on the shipping tracks and moving the traveling treads transversely inward until 110 they are entirely within the area of car clearance.

2. The process of preparing crawler vehicles for railroad shipment which consists in moving the vehicle into position on a railroad 115 car, disconnecting the traveling treads adjacent one end of the vehicle, moving each upper portion of the disconnected track longitudinally backward to clear the vehicle and piling such track on the car, moving the vehicle forwardly 120 along the traveling treads and onto the shipping tracks, locking the vehicle in place on the shipping tracks and moving the traveling treads transversely inward until they are entirely within the area of car clearance.

3. The process of preparing crawler vehicles for railroad shipment which consists in moving the vehicle into position on a rail- 125

- road car, disconnecting the traveling treads adjacent one end of the vehicle, moving each upper portion of the disconnected track longitudinally backward to clear the vehicle and piling such track, connecting the forward ends of the traveling tread with a shipping track on the car, moving the vehicle forwardly along the traveling treads and onto the shipping tracks, locking the vehicle in place 10 on the shipping tracks.
4. In combination a railroad flat car of such size as to fall within railroad clearance, a crawler vehicle having traveling treads of such size as when mounted on a railroad car 15 to extend beyond railroad clearance, the remainder of the vehicle falling within railroad clearance, a shipping track on the railroad car falling within railroad clearance and adapted to support the vehicle, the traveling treads being adapted to be disconnected at one or more points and the free end thereof to be connected to the shipping track to permit movement of the vehicle from the traveling treads onto the shipping tracks.
5. In combination a railroad flat car of such size as to fall within railroad clearance, a crawler vehicle having traveling treads of such size as when mounted on a railroad car to extend beyond railroad clearance, the remainder of the vehicle falling within railroad clearance, a shipping track on the railroad car falling within railroad clearance, and adapted to support the vehicle, the traveling treads being adapted to be disconnected 30 at one point and the free end thereof to be connected to the shipping track to permit movement of the vehicle from the traveling treads onto the shipping track, stop members adapted to be removably attached to the shipping track and to engage the running gear of the vehicle to prevent further movement thereof along such track.
6. In combination a railroad flat car of such size as to fall within railroad clearance, a crawler vehicle having traveling treads of such size as when mounted on a railroad car to extend beyond railroad clearance, the remainder of the vehicle falling within railroad clearance, a shipping track placed on the railroad car falling within railroad clearance and adapted to support the vehicle, the traveling treads being adapted to be connected to the shipping track to permit movement of the vehicle from the traveling treads onto the shipping track, elements on the shipping track adapted to interlock with the drive members on the vehicle to permit vehicle movement under its own power along the shipping tracks.
7. In combination with a crawler vehicle, articulated traveling treads adapted to enclose the vehicle running gear and adapted to be disconnected at a predetermined articulation joint, a shipping track adapted to support the vehicle to be connected to one end of the 55 60 65 70 75 80 85 90 95 100 105 110 115 120 125 130
- the articulated traveling treads, but not adapted to encircle the vehicle running gear.
8. In combination with a crawler vehicle, articulated traveling treads adapted to encircle the vehicle running gear and adapted to be disconnected at a predetermined articulation joint, shipping tracks adapted to support the vehicle to be connected to one end of the articulated traveling treads but not adapted to encircle the vehicle running gear, removable stop members associated with the shipping tracks adapted to engage the running gear to prevent movement thereof along the tracks.
9. In combination with a crawler vehicle, articulated traveling treads adapted to encircle the vehicle running gear and adapted to be disconnected at an articulation joint, a shipping track adapted to support the vehicle to be connected at one end of the articulated traveling treads but not adapted to encircle the vehicle running gear, members on the shipping tracks adapted to interlock with the drive members in the running gear to permit vehicle movement under its own power along the tracks.
10. In combination with a crawler vehicle, an articulated traveling tread or track adapted to encircle the vehicle running gear and adapted to be disconnected at an articulated joint, a shipping track adapted to support the vehicle, the traveling tread extending outwardly beyond the running gear, the shipping track extending outwardly only as far as the running gear.
11. The process of preparing crawler vehicles for railroad shipment which consists in moving the vehicle under its own power into position on a railroad car, disconnecting the traveling treads or tracks adjacent one end of the vehicle, moving each upper portion of the disconnected track longitudinally backward to clear the vehicle and piling such track on the car, connecting the forward ends of the traveling treads or tracks with a shipping track placed on the car, moving the vehicle forwardly along the traveling treads and onto the shipping tracks, and moving the traveling treads transversely inward until they are entirely within the area of car clearance.
12. The process of preparing crawler vehicles for railroad shipment which consists in moving the vehicle under its own power into position on a railroad car, disconnecting the traveling treads or tracks adjacent one end of the vehicle, moving each upper portion of the disconnected track longitudinally backward to clear the vehicle and piling such track on the car connecting the forward ends of the traveling treads or tracks with a shipping track placed on the car, moving the vehicle forwardly along the traveling treads and onto the shipping tracks.
13. The process of preparing crawler ve-

hicles for railroad shipment which consists in moving the vehicle into position on a railroad car, disconnecting the traveling treads adjacent one end of the vehicle, moving each 5 upper portion of the disconnected track longitudinally backward to clear the vehicle and piling such track connecting the forward ends of the traveling tread with a shipping track on the car, moving the vehicle forwardly along the traveling treads and onto the shipping tracks and moving the traveling treads transversely inward until they are entirely within the area of car clearance.

14. The process of preparing crawler vehicles for railroad shipment which consists in moving the vehicle into position on a railroad car, disconnecting the traveling treads adjacent one end of the vehicle, moving each 15 upper portion of the disconnected track longitudinally backward to clear the vehicle and piling such track connecting the forward ends of the traveling treads with a shipping track on the car, moving the vehicle forwardly along the traveling treads and onto 20 the shipping tracks.

15. The process of preparing crawler vehicles for railroad shipment with consists in moving the vehicle into position on a railroad car, disconnecting the traveling treads 25 adjacent one end of the vehicle, moving each upper portion of the disconnected track longitudinally backward to clear the vehicle, connecting the forward ends of the traveling treads with a shipping track on the car, 30 moving the vehicle forwardly along the traveling treads and onto the shipping tracks.

16. In combination a railroad flat car of such size as to fall within railroad clearance, 40 a crawler vehicle having traveling treads of such size as when mounted on a railroad car to extend beyond railroad clearance, the remainder of the vehicle falling within railroad clearance, a shipping track on the railroad car falling within railroad clearance and adapted to support the vehicle, the traveling treads being adapted to be disconnected at one or more points and the free end thereof at its articulation joints to be lined 45 with the shipping track to permit movement of the vehicle from the traveling treads onto the shipping tracks.

17. In combination a railroad flat car of such size as to fall within railroad clearance, 55 a crawler vehicle having traveling treads of such size as when mounted on a railroad car to extend beyond railroad clearance, the remainder of the vehicle falling within railroad clearance, a shipping track on the railroad car falling within railroad clearance, and adapted to support the vehicle, the traveling treads being adapted to be disconnected at one or more points and the free end 60 thereof to be connected to the shipping track.

to permit movement of the vehicle from the traveling treads onto the shipping track.

18. In combination with a crawler vehicle, articulated traveling treads or tracks adapted to encircle the vehicle running gear and adapted to be disconnected at a predetermined articulation joint, shipping tracks adapted to support the vehicle to be connected to one end of the articulated traveling treads, but not adapted to encircle the 75 vehicle running gear.

19. In combination with a crawler vehicle, articulated traveling treads adapted to encircle the vehicle running gear and adapted to be disconnected at an articulation joint, 80 a shipping track adapted to support the vehicle to be connected at one end of the articulated traveling treads but not adapted to encircle the vehicle running gear, members on the shipping tracks adapted to be lined with the drive members in the running gear to permit vehicle movement under its own power along the tracks.

Signed at Chicago, in the county of Cook and State of Illinois, this 24th day of April, 90 1928.
